UNITED STATES PATENT OFFICE

HIRAM T. FOLSOM, OF WENHAM, MASSACHUSETTS

BOOTJACK

Application filed January 16, 1929. Serial No. 332,869.

This invention relates to an improved bootjack or implement for removing boots.

A bootjack constructed in accordance with the present invention is adapted to permit the removal of boots with a minimum of required effort; when not in use, it may be folded into a compact unit which can be conveniently carried in a bag, suitcase, or the like or it may be hung upon the wall or in any desired location. Furthermore an implement of this character may be finished to have an attractive appearance comparable to that of the other accessories and elements of modern riding equipment.

15 This bootjack is characterized by the provision of a crosspiece adapted to form a toe engaging member and thus to permit the foot and leg to exert leverage in order to enable the easier removal of the boot from the same.

20 To this end, the pivotal connections between the outer supporting portion of the device and the inner boot engaging plate are so disposed that the device may be utilized with a maximum effectiveness. Furthermore this

25 implement is comparatively sturdy and will endure severe usage or shocks and blows when not in use, the arrangement of the crosspiece in substantial alignment with the ends of the legs being particularly advantageous in permitting the provision of an unusually durable structure for the indicated purpose.

The accompanying drawings may be referred to as an example of one preferred embodiment of the invention.

In these drawings:

Fig. 1 is a side elevational view of the improved bootjack in use;

40 Fig. 2 is an elevational view of the device in its folded position; and

Fig. 3 is a section on line 3—3 of Fig. 2.

Referring to the accompanying drawings and more particularly to Fig. 2 thereof, it may be seen that my improved bootjack comprises a support portion 1, having at one end an opening 2 to provide a suitable handle 3 which may be formed by the end of the support 1. This handle preferably is reinforced 45 against splitting by a tie bolt 5. Support 1

has a pair of legs 7 which bow outwardly and receive therebetween a plate 10.

Pintles 12 pivotally connect the legs of the support with the intermediate plate 10, suitable washers 13 being interposed between the legs and plate in order to permit the free swinging movement of these members in relation to each other. Preferably support 1 and plate 10 are both formed of wood and are of substantially the same thickness, being adapted to occupy a common plane when the device is folded.

In the region of the pivot elements 12, plate 10 has a boot receiving opening 14, which is provided with a substantially V-shaped heel-receiving end 15 toward the handle of the support 1, while a crosspiece 17, which may be an integral part of the plate 10, extends across the opposite end of opening 14. As shown in Fig. 3 the sides of the V-shaped heel-receiving portion of the opening are tapered toward each other, as designated by numeral 18 in order to permit the device more readily to grip the heel portion of a boot.

A suitable strap metal member 20 bridges the space between the legs 7 in order to form a stop for the plate 10 and cooperates with a swinging button 21 to hold the plate in substantially the same plane as the support.

Fig. 1 shows an implement of this character in use, the heel portion of the boot being engaged in the V-shaped end of the opening 14 and the toe thereof engaging the crosspiece 17 while the support 1 is inclined upwardly so that the ends of the legs support the boot receiving portion of the plate 10 above the floor, the opposite end of the plate resting upon the floor and being held in engagement therewith, for example, by the other foot. It is evident that the toe of the boot pressing upon the crosspiece 17 permits the exertion of additional leverage to aid in removing the heel portion of the boot from the foot of the user. The pivot elements 12 are positioned adjoining the forward portion of the foot so that the foot normally imposes an upward thrust upon the adjoining portions of the legs 7.

The device may be folded as shown in Fig.

2 to comprise a compact, substantially flat unit which may be readily packed or hung in any convenient location. The arrangement of the crosspiece 17 tends to reinforce 5 and protect the ends of the legs 7 so that there is less likelihood of the latter catching upon foreign objects and becoming broken; furthermore the sides of the plate 10 preferably are in juxtaposition to the legs, particularly the outer ends of the same, so that 10 an inward thrust upon the end of a leg is resisted by the corresponding side of the plate and so that the plate is positioned to avoid likelihood of an outward thrust upon 15 the leg end when the device is folded.

It is thus evident that I have provided a simple but highly effective bootjack which may readily receive an attractive finish, and which may be folded into a compact unit so 20 that it may be conveniently transported when desired.

I claim:

1. A device of the class described comprising a support having spaced legs joining a handle portion at one end, and intermediate plate, pivotal connections between the plate and legs, said plate having an opening in the region of the connections, the opening having a substantially V-shaped heel-receiving 30 portion at its end which is toward the handle, and a toe-engaging crosspiece at the opposite end of the opening, said support and plate being movable to a folded position in substantially a common plane with the crosspiece and the ends of the legs in alignment with each other.

2. A device of the class described, comprising a flat support having spaced legs joined by a handle portion at one end, an intermediate plate disposed between the legs, pivotal connections between the plate and legs, said plate having an opening in the region of the connections, the opening having a substantially V-shaped heel-receiving portion at its end which is toward the handle, and a toe-engaging crosspiece at the opposite end of the opening, said support and plate being movable to a folded position in substantially a common plane with the ends of 55 the legs in alignment with the outer edge of the crosspiece, the sides of the plate adjoining the edge of the legs being in close juxtaposition to the latter whereby the plate protects the legs.

3. A device of the class described, comprising a flat support having spaced legs joined by a handle portion at one end, an intermediate plate disposed between the legs, pivotal connections between the plate and legs, said plate having an opening in the region of the connections, the opening having a substantially V-shaped heel-receiving portion at its end which is toward the handle, and a toe-engaging crosspiece at the 60 opposite end of the opening, said support and

plate being movable to a folded position in substantially a common plane, said plate then having side portions in juxtaposition to the inner sides of the legs throughout substantially their entire extent and having the 70 crosspiece in alignment with the ends of the legs, whereby the plate protects the legs when the device is in its folded condition.

Signed by me at Boston, Mass., this ninth day of January, 1929.

HIRAM T. FOLSON.
